Primary Examiner — David Muller(74) *Attorney, Agent, or Firm* — Ogilvy Renault, LLP(57) **CLAIM**

The ornamental design for a two-piece portable urinal device, as shown and described.

DESCRIPTION

FIG. 1 is a perspective view of a first embodiment thereof;
 FIG. 2 is a rear view thereof;
 FIG. 3 is a front view thereof;
 FIG. 4 is a right side view thereof;
 FIG. 5 is a left side view thereof;
 FIG. 6 is a top view thereof;
 FIG. 7 is a bottom view thereof; and,
 FIG. 8 is a perspective view of a second embodiment thereof.
 The parts shown in broken lines are environmental only and
 form no part of the claimed design.
